(57) **CLAIM**

What is claimed is the ornamental design for an aircraft, as shown and described.

DESCRIPTION

FIG. 1 is a perspective view of an aircraft showing the new design;

FIG. 2 is a front view thereof;

FIG. 3 is a rear view thereof;

FIG. 4 is a side view thereof;

FIG. 5 is a second side view thereof;

FIG. 6 is a top view thereof; and,

FIG. 7 is a bottom view thereof.

The broken lines in the figures show portions of the aircraft that form no part of the claimed design.
